UNITED STATES PATENT OFFICE.

AUGUST HUGO GROSSENBACH, OF JERSEY CITY, NEW JERSEY.

REVERSIBLE DOUBLE-DESIGN NECKTIE.

1,011,148.

Specification of Letters Patent. Patented Nov. 13, 1913.

Application filed July 5, 1912. Serial No. 707,957.

To all whom it may concern:

Be it known that I, August Hugo Grossenbach, a citizen of the United States of America, and a resident of Jersey City, county of Hudson, State of New Jersey, have invented certain new and useful Improvements in Reversible Double-Design Neckties, of which the following is a specification.

This invention has reference to improvements in neckwear and pertains particularly to novel scarfs or neckties.

It is the special object of this invention to produce long braided or if desired knitted scarfs and neckties known as four-in-hand. These neckties or scarfs are usually tied by the wearer in a knot in such a manner that the broad portions or flaps of the tie are vertically hanging down. The tie is then tightly drawn so as to fit nicely around the neck and secured by a clasp. Braided ties or scarfs of this description which are relatively broad when new become gradually narrow by drawing the tie tightly and finally can not be used any more even if still in good condition.

In order to overcome the described deficiency I have devised a novel braided tie or scarf of the four-in-hand style which practically retains its entire width during use. In addition thereto the tie is reversible and of double design of which each preferably has a different color. The two designs are independently braided and united by intermediate cross strips uniting these narrow portions permanently and leaving independent sections between which are composed of two loose design portions. By virtue of these independent but loose sections with braided cross strips which are permanently connected the novel ties do not stretch to any perceivable extent and practically retain their full width during use.

The novel ties are usually braided from silks and represent a very neat and desirable article as will be fully described herein-after with reference to the accompanying drawing in which:

Figure 1 represents in elevation a braided scarf or necktie embodying in desirable form the present improvements. Fig. 2 illustrates in elevation a section of the braided tie with permanently connected cross strips. Fig. 3 is a longitudinal section on lines 3-3

of Fig. 2, and Fig. 4 is a similar view on line 4-4 of Fig. 2.

Similar characters of reference denote like parts in all the figures.

The novel reversible double design necktie or scarf consists preferably of an independently braided dark design and an independently braided light design which are united by permanently connecting braided cross strips in such manner that the face of the cross strips appearing on the surface of the dark tie portion is part of the light tie portion and vice versa, as is shown in Figs. 1 and 3. Thus a double necktie is produced uniting two, so to say, independent ties in one. The one tie portion forming an independent necktie simultaneously acts as the lining material for the other and vice versa. It gives body to the complete tie which results in a saving in material, labor and wages considering that two independent ties are contained in the one tie. Thus in fact the lining for two ties with the labor and wages involved is actually saved whereby the cost of production of the double tie is so reduced that even the finished article made of silks may be sold at a relatively moderate price.

In the drawing *a*, *a* represent sections of an independently braided dark portion of a double necktie; *b*, *b* are like sections of an independently braided light portion of the same. Both the dark and the light portion are so interlaced that the light narrow cross strips *b*¹, *b*² formed thereby appear on the surface of the dark tie portion while the dark narrow cross strips *a*¹, *a*², likewise formed appear on the surface of the light tie portion. These cross strips are formed by interlacing the light and dark portion as shown in Fig. 3. The braided edges *d*, *d*¹ permanently unite the black and white portion throughout the entire width of the necktie. Like interlaced edges *c*, *c*¹ are formed between the dark and light portion by the next cross strip. These cross strips are also provided on the neck band *e*. As shown in Fig. 3 the single sections, *a*, *b*, are loose and elastic and normally rest against each other with their inner surfaces. The cross strips *a*¹, *b*¹, however are formed by interlacing both parts so as to form the braided edges *d*, *d*¹ and *c*, *c*¹. Thus the cross strips connect both parts and their sections permu-

nently. These cross strips yield but little when the tie is drawn tightly and thus serve to retain practically the full width of the tie during use so that such ties can never become as narrow as woven ties of former construction. The hemming-in side edges are so braided that both colors appear alternately whereby a beautiful finished article is obtained of very neat appearance. These edges are also permanently united and aid in retaining the original width of the tie during use.

I claim as my invention:

1. A reversible double necktie comprising two independently braided parts, narrow cross strips formed by interlacing the said parts so that the cross strips of the one part appear on the surface of the other part and

vice versa, forming thus loose sections between said strips and connecting the same permanently.

2. A reversible double necktie comprising two independently braided parts, narrow cross strips formed by interlacing the said parts so that the cross strips of the one part appear on the surface of the other part and vice versa, and interlaced side edges whereby loose sections are formed between said strips permanently connected on all sides.

Signed at New York, N. Y., this 2nd day 20 of July 1912.

AUGUST HUGO GROSSENBACH.
